United States Patent Office

Des. 219,522
Patented Dec. 22, 1970

219,522

TRACK AND FIELD MARKER

Daniel M. Yeto, 1711 S. Quince St.,
Escondido, Calif. 92025

Filed Dec. 24, 1969, Ser. No. 20,646

Term of patent 14 years

Int. Cl. D21—03

U.S. Cl. D34—5

FIG. 1 is a perspective view of an assembled track and field marker, showing my new design,

FIG. 2 is a side elevational view thereof,

FIG. 3 is a top plan view thereof,

FIG. 4 is a bottom plan view thereof, and

FIG. 5 is a perspective view with the spike stowed.

I claim:

The ornamental design for a track and field marker, substantially as shown.
